DESIGN FOR A COASTER

Thomas A. Steeds, Cleveland Heights, and Robert C. Prall, University Heights, Ohio; said Prall assignor to said Steeds

Application April 20, 1946, Serial No. 128,816

Term of patent 7 years

(Cl. D44—10)

To all whom it may concern:

Be it known that we, Thomas A. Steeds and Robert C. Prall, citizens of the United States, residing at Cleveland Heights and University Heights, respectively, both in the county of Cuyahoga and State of Ohio, have invented a new, original, and ornamental Design for Coasters, of which the following is a specification, reference being had to the accompanying drawings, forming a part thereof.

Fig. 1 is a top plan view of the coaster, showing our new design;

Fig. 2 is a transverse section through the coaster; and,

Fig. 3 is a bottom plan of the coaster shown in Fig. 1.

We claim:

The ornamental design for a coaster, as shown.

THOMAS A. STEEDS.
ROBERT C. PRALL.
